UNITED STATES PATENT OFFICE.

SAMUEL C. POMEROY, OF ATCHISON, KANSAS, ASSIGNOR OF ONE-HALF TO
GEORGE M. SARGENT, OF EVANSTON, ILLINOIS.

MACHINE FOR PULVERIZING QUARTZ AND OTHER ORES.

SPECIFICATION forming part of Letters Patent No. 247,946, dated October 4, 1881.

Application filed March 17, 1881. (No model.)

To all whom it may concern:

Be it known that I, SAMUEL C. POMEROY, a citizen of the United States, residing at Atchison, in the county of Atchison and State of 5 Kansas, have invented certain new and useful Improvements in Machines for Pulverizing Quartz and Other Ores, of which the following is a specification.

My invention consists of a novel construction of machine for pulverizing quartz and other substances by means of violent percussion, and then collecting the resulting dust in a chamber having a series of partitions, in connection with a hollow column provided with a water-spray at the top and a receptacle at bottom, all of which will be understood by the following description.

In the accompanying drawings, Figure 1 is a vertical section of my machine. Fig. 2 is a view of the hollow cylinder and pulley for operating the radial arms and percussion-plates. Fig. 3 is a transverse section of the hollow cylinder, showing also the feed-opening, discharge-tube, and a slide to admit air to the cylinder. Fig. 4 is the bed-plate of the machine. Fig. 5 is a side view of the standard-bearing to support the shaft. Fig. 6 is a detached view of a portion of a radial arm carrying a percussion-plate.

Upon a suitable bed-plate, A, are bolted the standards B, having at the top bearings for the horizontal shaft C, which is provided with pulley D, or other means to operate the same. Upon the same bed-plate is fastened the hollow cylinder G, which may be three feet in diameter, and, say, eight inches in length, the dimensions being varied as desired. This cylinder has a smooth interior and is made very strong. It is provided with a feed tube or opening, H, placed inside of the path of rotation of the percussion-plates F, so that the feed will not be obstructed by said plates or the radial arms E. A small adjustable slide, S, is used to regulate the admission of air as desired. Attached to the circumference of this hollow cylinder is a dust-discharge tube, K, provided with a wire screen, U, to prevent the escape of coarse pieces of quartz. A deflect-

ing plate or elbow in the spout may be used for the same purpose. A slide, V, is used to 50 regulate the discharge. A trap on the cylinder G, provided with slide I, serves to collect grains of metallic gold.

The dust-chamber L has a series of partitions, M, for separating the falling dust into 55 different grades, the coarser dust falling first, while the finer and lighter dust is carried on to the more distant compartments.

The hollow shaft N is connected with the dust-chamber by means of a tube or passage, 60 m, through which the air passes to rise through the shaft. A small water-pipe, O, is crowned by a perforated hollow globe for the purpose of producing a spray to catch any residue of dust escaping from the chamber L with the 65 current of air. This dust is thus washed down to the receptacle R at the bottom of the shaft N.

Operation: The shaft C and arms E are first set in motion at full speed—say about three thousand revolutions per minute—and then 70 small pieces of quartz are fed in at the spout H, when the swiftly-revolving plates F by severe concussion speedily disintegrate the quartz, however hard, and drive the dust out through tube K into the dust-chamber L. 75

The broad concussion-plates F, Fig. 6, (which may be cast with the arms E,) serve as fans in a fan-blower and produce a strong blast from cylinder G, through the pipe K, chamber L, and shaft N, the amount of air being regulated 80 by the slide S above mentioned.

Having described my invention, what I claim is—

The combination of the hollow cylinder G, radial arms with percussion-plates thereon, a 85 dust and air escape tube or passage, a dust-chamber with partitions therein, and the hollow shaft N, provided with water-spray P and receptacle R, substantially as set forth.

In testimony whereof I affix my signature in 90 presence of two witnesses.

SAMUEL C. POMEROY.

Witnesses:

DANIEL BREED,
W. C. DUVALL.
